AUTOMATIC VOLUME CONTROL

Kenneth A. Chittick, Haddon Heights, N. J., assignor to Radio Corporation of America, a corporation of Delaware

Application December 16, 1933, Serial No. 702,674

1 Claim. (Cl. 250—20)

My present invention relates to gain control arrangements for high frequency signalling systems, and more particularly to automatic volume control circuits for radio receivers.

5 One of the main objects of my present invention is to provide an automatic volume control arrangement for a radio receiver wherein a direct current potential variation in a positive cold electrode circuit of the intermediate frequency amplifier is employed for regulation of the gain of a preceding high frequency transmission network.

Another important object of the present invention may be stated to be the provision, in a 15 superheterodyne receiver, of an automatic volume control network wherein direct current potential variations across a resistor in the screen grid circuit of the intermediate frequency amplifier is utilized for automatic control of the gain of a preceding high frequency amplifier.

20 Another object of the present invention is to provide an automatic volume control system for a superheterodyne receiver, the system utilizing direct current potential variations produced across a resistor in a positive cold electrode circuit of the second detector for high frequency amplifier gain regulation.

Still other objects of the present invention are to improve generally the simplicity and efficiency 30 of automatic volume control circuits; and to particularly provide a receiver wherein automatic volume control bias is secured without the use of an auxiliary control tube and which automatic volume control is constructed and assembled in a radio receiver in an economical manner.

35 The novel features which I believe to be characteristic of my invention are set forth in particularity in the appended claim. The invention itself, however, both as to its organization and 40 method of operation, will best be understood by reference to the accompanying drawings, wherein in several circuit arrangements of the present invention are shown and described.

In the drawings:—

45 Fig. 1 diagrammatically shows one circuit arrangement embodying the present invention,

Fig. 2 shows a modified form of the invention,

Fig. 3 shows a receiver embodying an additional modification of the invention,

50 Fig. 4 illustrates a further embodiment.

Referring now to the accompanying drawings, wherein like reference characters in the different figures designate similar circuit elements, there is shown in Fig. 1 one embodiment of the 55 invention, the embodiment comprising a super-

heterodyne receiver of conventional construction. The receiver, since conventional and well known to those skilled in the art, will only be briefly described. It comprises one or more stages of radio frequency amplification 1, these stages being uni-controlledly tunable in any well known manner. The input to the amplifier 1 includes the usual signal collecting circuit A, and, although shown as a grounded antenna system, is to be clearly understood as being capable of replacement by any other well known collector of signal energy.

5 The amplifier network 1 is followed by a network 2 which is designated "1st Det.-Local Oscillator", but it is to be clearly understood that 15 this network may embody a separate local oscillator and a separate first detector, or may be of the combined oscillator-detector type. In many cases, as where compactness is desired, the network 2 may be a combined oscillator-detector 20 circuit of the type disclosed and claimed by J. C. Smith in application Serial No. 654,421, filed January 31st, 1933. In the latter case the network 1 can be omitted, and the automatic volume control arrangement to be hereinafter described applied to the signal control electrode of the combined oscillator-detector.

25 The intermediate frequency output of the network 2, regardless of how obtained, is impressed between the input electrodes of the intermediate 30 frequency amplifier tube 3. The coupling between the network 2 and the input electrodes of tube 3 includes a pair of coupled resonant circuits 4, 5, both tuned to the operating intermediate frequency; and the tube 3 is of the pentode 35 type and is well known to those skilled in the art. The amplified intermediate frequency energy is transmitted from the tube 3 to the succeeding second detector 6 through a coupling network 40 which includes the coupled resonant circuits 7, 8, the latter being tuned to the operating intermediate frequency. The second detector output may be impressed upon an audio frequency amplifier and the amplified audio frequency energy reproduced in a reproducer of the electromagnetic or electrodynamic type.

45 The numerals 9 and 10 designate the positive and negative power supply leads connected between the power supply source, not shown, and the pertinent electrode circuits of the receiver. 50 It is to be clearly understood that the power supply source may be the usual power supply filter succeeding the rectifier tube when used with an alternating current supply, but the power supply source may also be a network adapted 55

for use directly with a commercial direct current or alternating current supply. In any case, the negative lead 10 includes in series therewith the reproducer field coil 11, the field coil being inserted in the lead 10 in such a manner that its positive side is connected to ground, as at 12. In this way the reproducer field coil is energized, and also provides a convenient means for securing a potential drop for other purposes.

10 The connections from the positive lead 9 and bleeder 9' to the various electrode circuits are not shown since those skilled in the art will readily understand how the bleeder is to be connected to provide a completely connected circuit.

15 The signal control electrode of tube 3 is connected to the negative side of the field coil 11 through a path which includes the tuned circuit 5, the lead 13, the resistor 14, and the lead 15. The cathode of tube 3 is connected to the positive side of resistor 14 through a path which includes the lead 16. The leads 15 and 16 are connected through a filter choke 17, and the latter functions to smooth out hum ripple in the power supply. The choke 17 is shunted across 25 the resistor 14, and the cathode of tube 3 is shown connected to the positive side of choke 17, while the lead 15 is connected to the negative side of choke 17.

20 The point on the resistor 14 to which the signal control electrode of tube 3 is connected is designated by the reference character P, and this point is represented as being negative in potential with respect to the point of resistor 14 to which the cathode of tube 3 is connected. The 25 screen grid electrode of tube 3 is connected to the lead 10 through a path which includes lead 18 and resistor R, while the anode of tube 3 is connected to the lead 10 by a path which includes the tuned circuit 7 and the lead 19. The 30 resistor R is shunted by a radio frequency bypass condenser 20, and a lead 21 conductively connects the negative side of resistor R to the gain control electrode of the radio frequency amplifier to be controlled.

35 A dotted line 22 is shown between the symbol in network 1 representing the control grid and the lead 21, and it will be clearly understood that this dotted line designates the gain control connection to the signal control grid of the controlled amplifier, or to the different signal grids if more than one controlled amplifier is used. The specific gain control connections between the controlled amplifier 1 and the lead 21 are not shown in detail because they are well known 50 to those skilled in the art and can readily be supplied, the lead 21 merely being designated "A. V. C." to clearly show the function thereof.

55 It is believed that the operation of the arrangement shown in Fig. 1 will be clear from the foregoing description, it being additionally pointed out that the intermediate frequency amplifier tube 3 has its signal control grid biased by connection to point P to such a value that the current flowing in the screen resistor R generates 60 just enough bias for the residual bias on the controlled amplifier network 1. The anode current of tube 3 is also reduced in like manner. When a signal is received the effective bias of the tube 65 3 is reduced, and allows more screen and anode current to flow. This effect increases the automatic volume control bias for amplifier control, and also the gain in the tube for intermediate frequency amplification.

70 75 The amount of the desired bias supplied by

resistor R is adjusted by adjusting the position of tap P.

Considering the operation of the automatic volume control arrangement somewhat more in detail it is pointed out that the amplifier tube 3 obtains its anode voltage and screen voltage by virtue of the voltage drop in the reproducer field coil 11, and that resistor R, across which the automatic volume control bias is developed, must be connected in close voltage proximity 10 with respect to the controlled amplifier tubes in order to produce the current polarity for automatic volume control bias. This anode and screen voltage may also be obtained from a suitable resistor or bleeder voltage not associated directly with the filter supply system, provided the respective voltage relation of resistor R to the cathode of the controlled amplifier tubes is maintained.

The arrangement shown in Fig. 1 acts like a 20 partial noise suppressor as the intermediate frequency gain in tube 3 is reduced when no signal is received. This is so because in the tube arrangement shown the control grid has more than normal bias in order to obtain the desired voltage drop in resistor R when no signal is obtained. When the signal voltage is impressed on the control grid, the effective bias is reduced and the gain of the tube is increased. Of course, the screen and anode of tube 3 may be reversed depending upon the characteristics of the tube. That is to say, the control resistor R may be disposed in the anode circuit, and the intermediate frequency energy taken out of the screen lead 18 by inserting the tuned circuit 7 in this lead 18. 35 In like manner the various functions of automatic volume control, voltage supply and amplifier stage may be obtained with any tube element or combination of tube elements suitable for this purpose.

In Fig. 2 is shown a modification of the invention wherein the construction and functions shown in Fig. 1 are embodied in the second detector circuit. The symbol 3' designates the second detector tube, which is of the same pentode type shown in connection with tube 3 in Fig. 1, the tuned intermediate frequency input circuit 8 being connected between the signal control electrode and the cathode through a negative potential source 14'. The cathode is connected to point P' on the bleeder resistor 30, one side of the latter being connected to the negative terminal of the power supply source, an intermediate point on the bleeder being connected to ground. The screen electrode lead 18' is connected to a proper positive potential point through a path which includes the radio frequency choke 31 and the primary winding 32 of the audio frequency transformer T, the transformer being arranged for connection to the usual audio frequency amplifier.

The anode of tube 3' includes the automatic volume control circuit, and the lead 19' thereto includes the radio frequency choke 33, the control resistor R₁ being connected between one side of the choke 33 and ground. The negative side of resistor R₁ is connected to the automatic volume control path which leads to the controlled amplifier. Appropriate radio frequency by-pass condensers 40 and 41 are connected respectively between the anode and cathode of tube 3' and between the screen grid and cathode of the same tube.

It will be noted that the second detector in Fig. 2 is biased off in the same manner as the tube 3

in Fig. 1, the signal functioning on the bias of tube 3' in the same manner. The screen and anode circuits may be reversed as to function in tube 3', as stated in connection with tube 3 of Fig. 1. The various functions of automatic volume control voltage supply and detection may be obtained with any tube element or combination of tube elements suitable for this purpose.

The operation of the arrangement in Fig. 2 is as follows: When signal voltage is impressed on the control grid, the effective bias is reduced which increases the anode current for automatic volume control bias. The screen current flow also increases. This increase in screen current increases the detecting properties of the tube, and relieves the noise suppression feature.

In Fig. 3 is shown another modification of the invention in which the tube 50 includes two sections which perform different functions in one envelope. This tube is of the type known as 6F7, and comprises a pentode section and a triode section having a common cathode. The control grid 51 and the control grid 52 of the pentode and triode sections respectively are connected together through a condenser 53. The cathode of tube 50 is connected to point P₁ on the divider resistor 54; the control grid 51 is connected through lead 55 to point P₂ on the divider for the normal grid bias; and the anode and screen of the pentode section of tube 50 are connected to proper positive potential points. The anode of the triode section of tube 50, which triode section functions to perform automatic volume control, is connected to ground through resistor R₁ across which the automatic volume control bias is developed. The control grid 52 of the automatic volume control section of tube 50 is connected to point P₃ on divider 54 through lead 56 to obtain the proper negative grid bias.

The amount of this bias may be sufficient to provide current in resistor R₁ for the residual grid bias for the amplifier tubes, or it can be of such a value that several volts of intermediate frequency voltage must be applied to the control grid before any automatic volume control bias is developed.

In operation, when signal is applied to both the control grids 51 and 52 in parallel the effective bias on the automatic volume control section of tube 50 is reduced as the signal is increased until current flows in resistor R₁ and generates control voltage. This volume control bias is applied to the preceding radio frequency amplifier, or amplifiers, and may also be applied to the intermediate frequency amplifier 60'. When bias is applied to the tube 60 the amount of bias desired to make the overall amplifier flat against signal voltage is obtained by tapping a portion of resistor R₁ for this bias. This last named arrangement is disclosed in co-pending application Serial No. 642,544, filed November 14th, 1932, of Chittick and Carlson. Here again the voltage supply may be obtained across a bleeder resistor and not across circuits shunting the rectifier filter system. In this modification the feature of noise suppression is not included. It is not necessary to explain the remaining portions of the circuit in detail, since they are either well known

to those skilled in the art from their diagrammatic showing, or correspond to elements already described and explained in connection with Figs. 1 and 2.

In the modification shown in Fig. 4 there is shown an arrangement wherein the tube 60 is substituted for the tube 50 of Fig. 3. The tube 60 is of the type known as 2A7, and the various tube electrodes are supplied with proper operating voltages as shown in Fig. 4, and as illustrated in Fig. 3. Signal voltage is applied to both control grids 61 and 62 connected in parallel through the coupling condenser 63. When the signal voltage increases, the effective bias on the automatic volume control grid electrode is reduced and current flows in resistor R₂ thus generating volume control bias.

This reduction in effective bias increases the anode current of the intermediate frequency amplifier section of tube 60 so that the tube also acts as a noise suppressor circuit. The additional intermediate frequency amplifier tube 60' may be included between the second detector and tube 60 as shown in Fig. 3. No further description of Fig. 4 is believed necessary in view of the fact that it functions in a manner similar to Fig. 3, with the exception of the noise suppressor function.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claim.

What I claim is:—

In combination with a network including a tube whose gain is to be automatically controlled in accordance with variations in amplitude of received signal energy, a control network including a tube having its input electrodes coupled to the output of said first tube, a power supply source including an impedance connected between the cathode of said control tube and a positive electrode of the latter, the cathode being connected to a point on said impedance to which the positive electrode is connected, means connected between said impedance and the signal control electrode of said control tube for maintaining the said signal electrode sufficiently negative with respect to said cathode in the absence of signal amplitudes below a desired level to maintain a minimum current flow through the circuit of said positive electrode, a control resistor connected in series between said impedance and the positive electrode of said control tube for developing from said minimum current flow the sole operating bias for the controlled tube which results in maximum sensitivity of the latter, a second positive electrode within said control tube, a signal output circuit connected to said second positive electrode, and a conductive connection between a point of negative potential on said control resistor and a gain control electrode of said first tube.

KENNETH A. CHITTICK.
